UNITED STATES PATENT OFFICE.

EDWARD B. HESS, OF NEW YORK, N. Y., ASSIGNOR, BY MESNE ASSIGNMENTS, TO
ROYAL TYPEWRITER COMPANY, INC., OF NEW YORK, N. Y., A CORPORATION OF
NEW YORK.

WRITING-MACHINE.

1,100,301.

Specification of Letters Patent. Patented June 16, 1914.

Application filed November 24, 1905. Serial No. 288,968.

To all whom it may concern:

Be it known that I, EDWARD B. Hess, a citizen of the United States, residing in the borough of Brooklyn, city of New York, State of New York, have invented certain new and useful Improvements in Writing-Machines, of which the following is a specification.

This invention relates to paper feeding and controlling devices of a writing machine having type-bars striking at a printing point on a transversely movable revoluble cylindrical platen.

It comprises front and rear feed rolls adapted to be simultaneously thrown into and out of action; marginal clamps movable longitudinally of the platen and capable of being moved away from the face of the platen out of the paths of the type bars; a pressure bar, that may contain a scale, located in front of and above the front feed rolls and preferably normally one letter space below the line of print, to which, however, it may be moved at will; a card and envelop holder movable longitudinally of the platen and capable in all its positions of being swung rearwardly so as not to interfere with free discharge of sheets from the machine. These and other features are hereinafter set forth in detail.

In the accompanying drawings: Figure 1 is a top plan view; Fig. 2, a bottom plan; Fig. 3, a front elevation; Fig. 4, an end elevation of the right-hand side of the carriage; Fig. 5, a view similar to Fig. 4, on a larger scale, omitting some of the parts; Fig. 6, a sectional view on line 6, 6, of Fig. 2 showing the feed rolls in engagement with the platen; Fig. 7, a similar view on line 7, 7, of Fig. 2 showing the feed rolls thrown out of operative position, and one of the margin clamps thrown up out of the paths of the type-bars; Figs. 7^a and 7^b are detail views showing modifications; Fig. 8, an elevation of the right-hand end of the carriage omitting some parts and showing the lever and gearing for throwing the feed rolls into and out of action; Fig. 9, a detail perspective view showing margin clamps and a rocking bar upon which they are carried; Fig. 10, a detail plan showing a modification of the manner of mounting the margin clamps upon their supporting bar; Fig. 11, an end view of the parts shown in Fig. 10; Fig. 12, is

a perspective view showing a modified construction and arrangement of the margin clamps, and also the intermediate card and envelop clamp mounted on the shaft carrying the margin clamps; Fig. 13, a rear elevation of one of these margin clamps on its bar; Fig. 14, a longitudinal section of the same; Fig. 15, an end view, the bar being in section; and Fig. 16, a bottom plan view; Fig. 17, is a bottom plan view of the card and envelop clamp mounted on the bar; Fig. 18, a side elevation thereof, the bar being in section; Fig. 19, a front elevation showing the platen, scale and pressure bar, ribbon vibrator and type bar guide.

a, a are the carriage side plates in which is mounted the platen *b*. *a'* is the actuating lever of line space devices, not shown. The ordinary paper table *b'* is mounted as usual upon a rod *b*² pivoted in the side plates. Beneath the forward edge of the table is an angle-plate *c* extending between the side plates and carrying a curved paper pan or guide *c'* (Fig. 6) extending around the under side of the platen and cut away opposite the back and front feed rolls. Lugs *d* on the under face of plate *c* (Fig. 2) form bearings for a shaft *d'*, carrying three downwardly and forwardly projecting arms *d*² having in their upper faces open trunnions or bearings *d*³ (Figs. 2 and 6) for a roll shaft *e* upon which are loosely mounted three pressure or paper-feed rolls *e'* adapted to coöperate with the platen through openings in the guide *c'*. The ends of the arms *d*² normally lie in transverse channels *f* in the face of an adjusting rod *f'* against which the arms are urged by coiled springs *g* enveloping the shaft *d'* and each having one end bearing against its arm *d*² and the other end attached to a collar *g'* provided with notches adapted to receive pins *g*² (dotted in Fig. 2) projecting from the under face of plate *c*. This allows an independent adjustment of the spring tension of each of the arms *d*².

The front feed rolls *h* are mounted upon a shaft *h'* carried in open bearings or trunnions *h*² in the ends of arms *h*³ fixed upon a rock shaft *h*⁴ extending between the side plates of the carriage. Applied to these arms are adjustable springs *h*⁵ by which their spring tension may be individually adjusted. The arms *h*³ extend forwardly and

upwardly from shaft h^4 and have extensions h^5 extending rearwardly and upwardly. The end of the rear arm h^6 of each of them occupies a transverse channel f^2 in the shaft f' against which the arms are urged by the springs h^5 . The two series of channels f and f^2 in the shaft f' are respectively upon opposite sides thereof, at angles to each other, and are off-set or staggered with reference to each other, Figs. 6 and 7. When in normal position (Fig. 6) with the rolls in operative relation to the platen, the arms d^2 and h^6 occupy the channels in the rod. When, however, the rod is turned through a partial revolution (Fig. 7) the arms ride out upon its periphery, the effect being to throw both the rear feed rolls e' and the front feed rolls h away from the face of the platen. The shaft f' may be conveniently partially rotated to effect this operation by providing upon one end a gear f^5 meshing with a circular rack f^4 on a pivoted lever arm f^3 , Figs. 2, 4, 8. By means of this organization the front and rear feed rolls, coöperating with the platen to feed or control the inserted sheets, may conveniently be thrown into or out of operative relation to the platen and will remain in either position subject to control by lever f^3 .

The pressure and alining bar i (shown as engraved with the usual scale) is carried upon the ends of arms i' (Figs. 3 and 4) jointed to arms i^2 arched to extend over shaft h^4 and rigidly secured at their rear ends to a rock shaft i^3 . Coiled springs i^4 extend from each arm i' to the rock shaft i^3 and, by their reaction tend always to draw the pressure bar against the face of the platen and also to hold it in its lowermost position which is, by preference, one letter space below the printing line, this position being sufficiently far below the printing line to prevent the bar, in any way, interfering with the ribbon or ribbon vibrator employed in front stroke machines.

To hold the scale pressure bar in lowermost position, I prefer also to use heavier springs i^5 which perform that function and are connected to the respective arms i^2 and to the frame (Fig. 5).

Attached to rock shaft i^3 is a lever i^6 having a projection i^7 from its axis engaging a stop pin on the side plate of the carriage to limit upward movement of the lever and consequently the lowermost position of the pressure and scale bar. By depression of lever i^6 , the pressure bar may be lifted to the line of print for the purpose of adjusting the paper, making corrections, etc., and, during such movement its pressure against the platen is maintained by springs i^4 . This bar, normally exerting spring pressure against the platen in front of the feed rolls h and but one

letter space below the line of print, not only coöperates with the front and rear feed rolls to afford complete control and ready adjustment of inserted sheets, but also serves to grip the paper close to the line of print after the paper has passed out of engagement with the front rolls permitting, with certainty, proper printing close to the bottom edge of the sheet. The bar, having a straight edge, may be utilized in alining the paper when it is desired to make insertions and corrections: and since it may be thrown to the line of print by operation of lever i^6 it may be used, in that way, to afford great accuracy, and also acts as a certain guide in adjusting the paper for printing on ruled lines. It may, under some circumstances, be desirable to throw the pressure bar away from the platen when the front and rear feed rolls are thrown out of action. This may be done in any convenient way, for instance as shown in Fig. 7, where extensions i^8 from the scale pressure bar bear against the extreme ends of arms h^6 so that when these arms are thrown down to carry feed rolls h away from the platen, the bar is also moved from the face of the platen. The same operation may be carried out in other ways. For instance, as in Fig. 7^a the ends of arms h^6 may extend upward and engage the rear face of the bar.

The construction and arrangement of margin clamps illustrated in Figs. 1 to 11 are as follows: Extending between the side plates in rear of the platen, somewhat above the plane of its axis, is an angular or squared shaft j adapted to rock in bearings in the side plates. A plate spring j' bearing on flat faces of shaft j holds it in either of two positions. The margin clamps are each composed of a flat curved arm k extending around the upper front face of the platen and having lugs k' turned up at its sides to form bearings for the shaft of a clamp roller k^2 that extends through an opening in the plate arm k and bears upon the front face of the platen. This arm is attached to a sheet metal arm m extending parallel with the axis of the platen and having a thumb piece m' and a rearwardly extending portion m^2 , the rear end of which embraces the squared shaft j (Fig. 9) and has a laterally extending part m^3 , upturned at its end m^4 and apertured to embrace the squared shaft. Between the part m^3 and the squared shaft is interposed an arched plate spring m^5 . The parts m^2 , m^4 , forming portion of the left hand margin clamp, are apertured to conform to the sides of the squared shaft so that when this clamp is thrown upwardly, the shaft is rotated through a quarter turn in which position, with this clamp elevated, the shaft is held by the plate spring j' . The right hand margin stop is similarly constructed with the exception that the aper-

tures in the portions m^2 , m^4 are round, the arched plate spring m^5 , in this instance, serving to hold this margin clamp, which is capable of turning on the squared shaft, in either 5 its upper or lower position. By holding the margin clamp at the left down with one hand, the operator may throw the right hand clamp up out of the paths of the type bars, permitting additional printing in the 10 right hand margin, the shaft j' in this case remaining stationary. When the right hand clamp is held down, the left hand one may be thrown up, the shaft j' turning with it. When it is desired to throw both clamps up, 15 it is only necessary to lift the left hand one and the shaft j , being partially rotated, carries the right hand clamp with it. The clamps are slidably mounted on the shaft and are frictionally held in any position to 20 which they are longitudinally adjusted by the spring m^6 .

Since it may be desirable under some circumstances, I have provided that when the feed rolls and scaled pressure bar are moved 25 away from the platen, the margin clamps may also be retracted. This may be conveniently done as illustrated in Fig. 8, which shows a cam face f^6 , on the inner side of lever f^5 , working against the end of an 30 arm j^2 fast on the end of the margin clamp carrying shaft j . When the lever is rocked to move the feed rolls away from the platen the cam lifts the arm and the margin clamps are also withdrawn from the face of the 35 platen. These clamps are shown as having rollers bearing on the platen. They may, of course, be of any appropriate construction. Under some conditions it may be desirable 40 that they be normally held somewhat away from the platen. This may be conveniently accomplished by adjustable means consisting of a projection from the front face of shaft j , near its end (or near each end) abutting against the paper pan or guide c' near 45 its edge. This projection may consist (Fig. 7b) of a slotted plate j^3 attached to the front face of j by a clamp bolt j^4 .

Figs. 10 and 11 show a modification. In this case a plate spring m^6 riveted to the outer 50 side of part m^8 has mounted in its ends rollers m^7 that run on the flat faces of the bar. The clamps will be properly held with reference to all adjustments described, but their movements endwise of the bar are facilitated.

Figs. 12 to 16 show further modifications of the margin clamp devices. The clamping surfaces coöperating with the platen are curved metal plates, which may, however, be 60 equipped with rolls similar to those k^2 , Fig. 6. The end of each of the clamping plates N is narrow, the inner edge n is shown as lying in a plane at right angles to the platen axis, and the outer edge n' is curved or inclined outwardly. The inner edge above or

back of the curved part of the arm is cut back as at n^2 forming a recess for clearance of the paper leaving the platen, and the rear edge of such recess has a downwardly inclined part n^3 serving to deflect the paper. 70 The clamp arm thus formed is at the rear turned down at each side to receive a hinge pin n^4 , passing also through upturned lugs n^5 on the top of a roller box traveling on the fixed squared shaft N' . Between the sides 75 of this roller box below the shaft are mounted rollers n^6 that run upon the under flat face of the shaft. A roller n^7 turning in an opening in the top of the box bears on the upper face of the shaft and is carried by a 80 flat spring whose ends are seated in apertures in the lugs n^5 . A handle N^2 , or knob, is applied to the plate N at the rear and a flat spring N^3 attached to the rear wall of the box works against the rear edge of plate 85 N and holds it depressed or elevated. When elevated the clamp is out of the paths of the type bars. From the rear of each rocking margin clamp arm (or the box on which it is pivoted) projects a gage N^4 the inner 90 edge of which is at right angles to the platen axis, and preferably slightly nearer the center of the machine than is the parallel wall of the recess n^2 that affords clearance for passage of sheets passing under the 95 clamps. When the gages N^4 are set with reference to a fed sheet, clearance of the sheet as it leaves the margin clamps is assured.

The intermediate or central card and envelop clamp O is similarly mounted on the shaft N' , but is divided transversely and its front paper holding part O' hinged somewhat in front of its roller box by which it is mounted on the shaft. 100

o indicates such hinge connection (Figs. 12, 17 and 18) and o' is a projection at rear edge of O' which, when O' is raised, passes through an opening o^x in the top plate of part O and depresses leaf spring m^x the reaction of which upon projection o' will hold the part O' elevated. When part O' is down, in working position, spring m^x bears against its under face below its pivot and holds it down. When retracted it is folded backwardly to a substantially horizontal position quite out of the way of sheets discharged from the platen. Its front end which bears against the platen is preferably curled upwardly as at o^2 . 110

z , Fig. 4, indicates the usual rack release lever and y a rocking rack bar.

I claim as my invention:

1. The combination with the platen of a visible typewriting machine, of front and rear feed rolls, sets of rocking arms in which they are respectively mounted, spring tension devices for each set of arms, an adjusting device for each spring tension device, a transversely channeled rock-shaft with op- 125

- positively obliquely disposed seats with which the arms of the front and rear feed rolls respectively engage, a gear upon the end of the shaft and a shaft rocking lever having an 5 intermeshing gear.
2. The combination with the platen of a visible typewriting machine of arms rocking about an axis in rear of the platen and extending forwardly and downwardly, a 10 rear feed roll mounted upon a shaft having bearings in said arms intermediate their free ends and said axis, bell-crank levers mounted to rock about an axis below the platen and having arms extending upwardly and 15 forwardly and arms extending rearwardly, a front feed roll carried by a shaft having bearings in the forwardly extending arms of the bell-crank, a transverse rotatable shaft having means for acting upon the rearwardly extending arms of the bell-crank, and upon the free ends of the arms carrying 20 the rear feed roll to throw the front and rear feed rolls away from the platen, and means by which the operator may rotate 25 said shaft.
3. In a writing machine, paper feed spring pressed pressure rolls, a releasing shaft provided with gear teeth and by rotation of which the pressure rolls are moved 30 away from the platen, combined with a rocking part having intermeshing gear teeth.
4. In a visible writing machine the combination with a rotatable platen having its 35 printing side at all times in view of the operator, of a combined pressure, alining and scale bar, located adjacent and below the normally visible line of print, means for moving the scale bar from normal position 40 to the line of print and spring means acting to press the scale bar yieldingly against the surface of the platen in either its depressed or elevated position and while moving from the latter to the former position.
- 45 5. In a visible typewriting machine, a system of pressure devices comprising front and rear spring-pressed feed rolls, an independently mounted scale bar independently spring-pressed against the platen and means 50 for moving them all away from the surface of the platen against the tension of their springs and automatically holding them in removed position.
6. The combination with the platen of a 55 visible typewriting machine of a pressure bar normally located below the printing line, upwardly extending arms by which it is carried, rearwardly extending arms to which the upwardly extending arms are pivoted, a rock shaft to which the rearwardly extending arms are attached, spring acting means tending constantly to force the pressure bar against the platen, and means for 60 rocking the shaft to elevate the pressure bar 65 toward the printing line.
7. A visible writing machine comprising the combination of a platen, a pressure bar normally located below the line of print, a light spring for holding the bar yieldingly against the face of the platen, a spring of superior strength whose reaction holds the bar in normal position, and means for moving the bar to the line of print. 70
8. In a visible typewriting machine, a system of pressure devices comprising front 75 feed rolls and their springs by which they are pressed against the platen, rear feed rolls and their springs by which they are pressed against the platen, an independently mounted scale bar and its springs by which 80 it is pressed against the platen and means for moving all said feed rolls and the scale bar away from the surface of the platen against the tension of their respective springs. 85
9. In a front strike typewriting machine, the combination of a rotatable platen having its printing side at all times in view of the operator, an alining scale and pressure bar normally located below the line of print, pressure feed rolls and margin clamps and means for moving the bar to the line of print independently of any movement of the platen feed rolls and margin clamps. 90
10. In a visible writing machine, the combination of a rotatable platen having its 95 printing side at all times in view of the operator, a scale bar normally located below the line of print and yieldingly pressed toward the exposed printing side of the 100 platen, margin paper holding devices extending down in front of said bar when the latter is in normal position below the line of print and means for moving the bar toward the line of print while still overlapped by the margin devices. 105
11. In a visible typewriting machine, the combination of individual tensioned pressure rolls at the front and rear of the platen and below the horizontal axis thereof, collectively tensioned margin devices located above the platen, a scale and pressure bar spring-pressed against the platen and located at the front of the platen normally 110 below the line of print and means for moving the scale bar and pressure rolls away from the platen. 115
12. Margin clamp devices for a typewriting machine comprising the combination with the platen of an angular shaft parallel with the platen axis and a clamp carrier embracing the bar and having a spring-pressed roller bearing against the bar, whereby the clamp carrier is held in desired position and is capable of ready adjustment longitudinally of the platen. 120
13. In a visible typewriting machine, a pair of margin paper holding devices mounted above the line of print, a transverse bar extending across the carriage and along 125 130

which the margin holding devices are adjustable, an alining scale and pressure bar normally located below the line of print but adapted to be moved thereto, spring-pressed pressure devices located below the pressure bar and means for throwing the pressure devices out of engagement with the platen and moving the scale bar away from it.

14. The combination with the platen of
10 a visible writing machine, of a margin clamp
adjustable longitudinally of the platen and
extending from the rear of the platen over
the front thereof to below the printing line,
a scale spring-pressed against the platen be-
15 low the line of print and overlapped by the
margin clamp, a card holder or clamp ad-
justable longitudinally of the platen, ex-
tending from the rear of the platen over
its front face, terminating above the line of
20 print and mounted so as to be movable rear-
wardly to inoperative position, and means
for moving the scale bar to the line of print.

15. The combination with the platen of a
visible writing machine of a margin clamp
25 adjustable longitudinally of the platen and
extending from the rear of the platen over
the front thereof to below the printing line,
a scale below the line of print and over-
lapped by the margin clamp, and a card
30 holder or clamp adjustable longitudinally
of the platen, extending from the rear of the
platen over its front face and terminating
above the line of print and mounted so as
35 to be movable rearwardly to inoperative
position.

16. In a writing machine the combination
with the platen, of margin clamp devices
comprising a clamp supporting bar parallel
with the axis of the platen, a clamp carrier
40 mounted upon and having a roller contact
with the bar for longitudinal adjustment
thereon and a clamping arm hinged to the

carrier and adapted to be moved away from
the platen out of the paths of the type bars.

17. In a visible writing machine, the com-
bination of a platen, a scale bar located be-
45 low the line of print, a margin clamp and
paper guide located above the line of print,
adjustable longitudinally of the platen, ex-
tending down across the line of print beyond
50 the upper edge of the scale bar which it
normally overlies and having a clearance
space with a deflector at the rear thereof to
direct paper leaving the platen, and means
55 for moving the scale bar up between the sur-
face of the platen and the clamp and guide
to the line of print.

18. In a visible writing machine, a mar-
gin clamp having a part adapted to engage
the paper on the platen and a supporting 60
arm for said part cut away to form a clear-
ance space for a sheet leaving the platen
and a paper deflector located at the rear of
the clearance space and over which the sheet
65 passes as it is delivered from the platen and
means permitting the clamp and deflector to
be folded rearwardly into inoperative posi-
tion.

19. In a visible writing machine the com-
bination with the platen, of a card or en-
velop clamp, adjustable longitudinally of
the platen, hinged intermediate its length
so that its leading free end may be folded
70 back to inoperative position out of the path
of the paper, and having a deflector for
guiding the paper as it leaves the platen and
means for holding the clamp in inoperative
75 position.

In testimony whereof, I have hereunto
subscribed my name.

EDWARD B. HESS.
